New York, N. Y., a corporation of Virginia

Application January 16, 1934, Serial No. 706,794
Renewed February 17, 1936

9 Claims. (Cl. 242—64)

This invention relates to a roll supporting device of the magazine reel type for rotatably supporting a plurality of web rolls for feeding the webs to the press.

The principal objects of the invention are to provide a slow speed spider shifting device for side register, in combination with a higher speed spider shifting device for moving one or both spiders for rolls of different widths, and to provide simple means for operating the retractable chuck which is carried in one of the spiders to facilitate the mounting of the paper rolls.

Other objects and advantages of the invention will appear hereinafter.

Reference is to be had to the accompanying drawings, in which

Fig. 1 is a front elevation of a web roll supporting reel comprising a preferred embodiment of this invention;

Fig. 2 is an end view of the same;

Fig. 3 is a sectional view through the center of the means for changing the speed of operation for the two purposes mentioned;

Fig. 4 is a sectional view on the line 4—4 of Fig. 3;

Fig. 5 is a sectional view on the line 5—5 of Fig. 3;

Fig. 6 is a sectional view on the line 6—6 of Fig. 3;

Fig. 7 is a sectional view of the retractable chuck mechanism, and

Fig. 8 is a sectional view of the same on the line 8—8 of Fig. 7.

This invention is best fitted for use with a newspaper printing press where it is necessary to replenish the rolls efficiently and with ease and to shift the spiders to accommodate rolls of different widths as well as to shift them for side register, but the invention may be applied to the feeding of webs outside the newspaper art.

Between editions, it often happens that it is necessary to change the roll width in order to obtain a different number of pages on the printed product. In a previous application (Serial No. 610,748, filed May 12, 1932, now Patent 1,957,122, dated May 1, 1934), I have shown and described a web roll stand having means for shifting the spiders for side register or for shifting one of them to accommodate a roll of a different width. When shifting the two spiders for side register, no high speed is desired, but this invention is designed to use the same mechanism and yet provide a higher speed for shifting one of the spiders to accommodate rolls of different widths. The operating lever of this shifting device operates

through a path which is normally occupied by a web roll so that it prevents the lever from being thrown to neutral or to the high speed when the roll is in place and the machine being operated to improve the side register.

The usual pedestals 1 and 2 are shown to provide supports for the central main shaft 3 of the reel by means of rotatable bearings 4 fixed to the shaft 3. A worm wheel 5 is secured to the shaft 3 which meshes with a worm 6 driven by a motor 7. This is the usual means for rotating the reel. Two spiders 8 and 9 make up the rest of the reel and they are mounted on the shaft 3 and secured against rotation thereon by a feather 10. However, they are capable of longitudinal motion, either together or independently along the shaft. Each spider 8 and 9 carries, as usual, a plurality of rotatable spindles 11 and 12 on which may be mounted the paper rolls R in such a manner that one of them may feed the web to a printing press, not shown.

On one of the bearings 4 is mounted a motor 13 which rotates with the bearing and with the reel as the latter is turned. The motor shaft carries a pinion 14 meshing with a gear 15 secured to a splined shaft 16, the other end of which shaft is supported in the other bearing block 4 at the other end of the shaft 3. Figs. 3 to 6 show that the shaft 16 penetrates the spider 9 through a cavity, at the ends of which are mounted thrust washers 17 and 18. In this cavity, on the shaft 16 is fixed a worm 19 which is secured against rotation with respect to the shaft 16 by keys 20. These keys are held in place by the thrust washers 17 and 18 so that when the spider 9 is moved longitudinally, these keys travel along the shaft with the worm 19. The worm 19 meshes with a straight face gear 21 rotatably mounted on the shaft 22. This shaft 22 is supported by a bearing in the spider 9 and a removable bearing 23 secured to the spider. By appropriate shoulders on the shaft 22, the removable bearing 23 serves to keep the shaft fixed in longitudinal relation.

On the upper end of the shaft 22 is mounted a pinion 24 meshing with a rack 25 secured to and extending along the shaft 3. On this shaft 22 is slidably splined a clutch 26. It carries teeth 27 at one end cooperating with complementary teeth 28 on the gear 21 and teeth 29 on the other end for cooperating with complementary teeth 30 of a gear 32, which also is rotatably mounted on the shaft 22. These parts of course are duplicated at the other end.

A loosely mounted shoe 33 cooperates with a 55

circumferential center groove of the clutch 26. The shoe is eccentrically mounted in a hole 34 of a head on a shaft 35 whereby the partial rotation of the shaft 35 will cause the shoe 33 to 5 shift the clutch 26 either up or down on the shaft 22, as indicated in Fig. 3. The oscillation of the shaft 35 is accomplished by a handle 36 clamped thereto and provided with a spring-seated retractable dowel 37 which may be placed 10 in any one of three holes 38 in a frame 39 fixed to the spider.

In full lines in Fig. 5 the handle 36 is shown in the neutral position so that the clutch 26 is not in contact with either of the two driving 15 gears 21 or 32. The gear 21 meshes with a smaller gear 40 fixed on a shaft 41 and on this shaft is also fixed, or integral, a larger gear 42 meshing with the gear 32. This constitutes a back gearing as will be obvious. When the 20 handle 36 is thrown from the neutral to the position marked "Slow" in Fig. 5, it is evident that the clutch teeth 27 and 28 will cooperate so that the clutch is directly connected to the gear 21. Now when the motor 13 is connected with its 25 power, power is transmitted from it to the shaft 16, worm 19, gear 21, and clutch 26 to rotate the shaft 22 at a slow speed to cause the pinion 24 to walk along the rack 25 for adjusting side register. The motor 13 is reversible so that the 30 spider may be shifted in either direction. Of course, in this case both spiders are connected with the power by the operation of both handles 36. When the handle 36 is in the slow position (Fig. 5) for side register and the rolls are in 35 place on the reel, the handle cannot be turned back to neutral position because it would engage the end of the roll (see Fig. 1).

When it is desired to shift either spider to adjust the reel for rolls of different width, the 40 above described mechanism is too slow and for that purpose the back gearing and double clutch are introduced. In this case the handle 36 is moved to the position marked "Fast" in Fig. 5 and the clutch 26 will move in the opposite direction so that the teeth 29 and 30 are in mesh 45 and the power will be transmitted from the shaft 16 through the worm 19, gears 21, 40, 42 and 32 at a higher rate of speed. It is apparent that the chain of gearing is such that the clutch 26 will be made to run faster than when it was 50 clutched directly with the gear 21 and that it causes the shaft 22 to rotate at a higher speed. This walks the pinion 24 along the rack 25 and shifts the spiders, or one of them, at a faster 55 rate.

It will be noted that there is a handle 36 at each end of the machine and it is intended ordinarily to employ this higher speed for one spider at a time leaving the other clutch in neutral position. A cap 43 is provided for covering the 60 openings in the spiders 8 and 9 which houses the pinion 24. A cover 44 is used to close the housing containing the gear shift. Each spider, of course, carries a similar shifting arrangement as has been stated.

A simple means is also provided for operating each tractable spindle 12 which is carried in one of the spiders 9 to facilitate the mounting of the paper rolls. This is shown in Figs. 7 and 8. In 70 this case the spider 9 has a hole 45 bored in the end of each of its arms for the mounting of the chuck 46. A keyway 47 in this chuck cooperates with a guide pin 48 to permit short longitudinal motion but to prevent any rotatable motion of the chuck. A worm 49 is centrally located in

chuck 46 and has one end supported in a hole 50 and the other carried in plug 46a which is held in place by a screw 52, half in the plug and half in the chuck. A hand wheel 53 is pinned to the outside end of the worm 49 for the purpose of 5 rotating it. The worm 49 rotates a gear 54 on a transverse shaft 55 mounted in bushings 56 and 57 on the spider 9. On one end this shaft has attached to it a collar 58 and on its other end is an operating arm 59. This arm 59 carries a 10 retractable dowel 60 which may be operated by a handle 61 against the opposition of a spring 62. A plate 63 is secured to the spider 9 and provided with a hole 64 to receive the dowel pin. When the dowel pin is inserted in the hole 64 15 the chuck is then in its operative position and stays in that position. This places the spindle 12 in the dotted line position in Fig. 8 or the full line position in Fig. 1.

The outer race of a ball bearing 65 at the 20 end of the chuck 46 is secured to the spindle 12 by a washer 66. The inner race is carried on the chuck 46 and secured thereto by a washer 67. Of course, a similar construction is provided on each arm of the spider. Therefore, it is 25 apparent that the spindles 11 carried in the spider 8 may be stationary longitudinally but rotatable on their axes. Also when the arm 59 is moved to such position that the dowel 60 enters the hole 64 the hand wheel 53 will be free 30 to be turned to move one of the spindles 12 toward or from the paper roll in an axial direction. This constitutes a simple construction so that a finer regulation of the rotatable chucks 35 may be obtained by a single means.

Having thus described my invention and the advantages thereof, I do not wish to be limited to the details herein disclosed, otherwise than as set forth in the claims, but what I claim is:—

1. The combination with a web roll supporting 40 reel comprising movable ends for supporting the web rolls, of means for moving one or both of said ends at two different speeds.

2. In a stand for paper rolls, the combination of a support adapted to carry a paper roll, means 45 for moving said support to bring a fresh paper roll into the proper position for feeding the web therefrom, said support comprising a pair of ends movable along the support, means for moving said ends along the support slowly for side-registering 50 the roll, and means for moving said ends along the support rapidly for the purpose of shifting them to accommodate rolls of different lengths.

3. In a paper roll support, the combination of a central shaft, a pair of spiders on said shaft 55 having means for supporting one or more web rolls, means for rotating the shaft, means rotatable with the shaft for moving the two spiders slowly for the purpose of side-registering the rolls, and means whereby one of said spiders can be 60 moved more rapidly along the shaft for the purpose of accommodating rolls of a different length.

4. In a web roll supporting device, the combination of a central shaft, a pair of spiders longitudinally movable on the shaft and having means 65 for supporting one or more web rolls between the spiders, means rotatable with the shaft for moving the two spiders simultaneously along the shaft at a slow speed for side register purposes, and means cooperating therewith and driven thereby for moving either one of said spiders along the shaft at a higher speed for accommodating the device for supporting rolls of a different length. 70

5. In a reel for supporting web rolls, the combination with a central shaft, means for rotating 75

it, and a pair of spiders movably mounted on said shaft, of a motor rotatable with the shaft, a rack fixed to the shaft, each spider carrying a pinion meshing with said rack and independent means 5 on each spider for connecting the motor with the corresponding pinion, whereby the motor can be used to move both spiders through the operation of the pinions on the rack for side register or to move one of the spiders to accommodate the reel 10 to rolls of different lengths.

6. The combination with a rotatable reel comprising a shaft and two spiders movable along the shaft and adapted to support web rolls between them, of a motor carried by, and rotatable with, the shaft, a second shaft located parallel with the first shaft and driven by the motor, a third shaft at an angle to the first two shafts, gearing 15 for driving the third shaft from the second shaft at two different speeds, a pinion on the third shaft, a longitudinal rack carried by the first shaft with which said pinion meshes, a handle located adjacent to the end of a roll on the reel and having connections for shifting the gearing and being movable to three positions, a neutral position and one on each side for driving the pinion slowly or rapidly, the neutral and fast driving positions of the handle being such that a roll on the reel will be engaged by the handle if it is attempted to be turned to either one of those positions when the reel is loaded.

7. The combination with a rotatable reel comprising a shaft and two spiders movable along the shaft and adapted to support web rolls between them, of a motor, a second shaft driven by the motor, a third shaft, gearing for driving the third shaft from the second shaft at two different speeds, a pinion on the third shaft, a longitudinal rack carried by the first shaft with which said pinion meshes, a handle on a spider having connections for shifting the gearing and being movable to three positions, a neutral position and one on each side for driving the pinion slowly or rapidly, the neutral and fast driving positions of the handle being such that a roll on the reel

will engage the handle and prevent its being turned to either one of those positions when the reel is loaded.

8. The combination with a rotatable reel comprising a shaft and two spiders movable along the shaft and adapted to support web rolls between them, of a motor carried by, and rotatable with, the shaft, a second shaft located parallel with the first shaft and driven by the motor, a third shaft at an angle to the first two shafts, gearing 10 for driving the third shaft from the second shaft at two different speeds, a pinion on the third shaft, said pinion being mounted on a spider, a longitudinal rack carried by the first shaft with which said pinion meshes, a handle located adjacent to the end of a roll on the reel and having connections for shifting the gearing and being movable to three positions, a neutral position and one on each side for driving the pinion slowly or rapidly, the neutral and fast driving positions of the handle being such that a roll on the reel will be engaged by the handle if it is attempted to be turned to either one of those positions when the reel is loaded.

9. The combination with a reel for supporting 25 web rolls comprising a rotary shaft and two spiders movable along the shaft for carrying the web rolls, of a motor mounted to rotate with the shaft, a parallel shaft connected with the motor to be operated thereby, each spider having a recess therein, a worm in each recess, a key by which the worm is slidably keyed to the second shaft, a pair of thrust washers in each recess at the ends of the worm for holding the key and causing it to move along the shaft with the worm, 30 and means operated by each worm for moving its spiders longitudinally of the shaft.

HENRY A. WISE WOOD.
